UNITED STATES PATENT OFFICE.

FARMER DORSEY, OF WICHITA, KANSAS, ASSIGNOR TO THE IMPERIAL BRASS MANUFACTURING COMPANY, OF CHICAGO, ILLINOIS, A CORPORATION OF ILLINOIS.

AUTOMATIC ACETYLENE GENERATOR.

Application filed July 26, 1926. Serial No. 124,878.

My invention is concerned with certain new and useful improvements in automatic acetylene generators of the type shown in my application, Serial No. 525,566, filed December 29, 1921, and is designed to produce a structure that shall be somewhat simplified without in any way sacrificing its capabilities and accuracy of operation. To this end, it comprises certain new and useful combinations of elements, which will be described in detail and particularly pointed out in the annexed claims.

To illustrate my invention I annex hereto two sheets of drawings in which the same reference characters are used to designate identical parts in all the figures, of which,

Fig. 1 is a perspective view of the complete apparatus;

Fig. 2 is a central vertical sectional view through the carbide hopper, but on a larger scale;

Fig. 3 is a central vertical section through the pressure regulator; and

Fig. 4 is an enlarged section through the vibrator and the adjacent portion of the mechanism.

In carrying out my invention in its preferred form, the water tank 10 is substantially constructed, preferably with the upper portion in the shape of the frustum of a cone, to give the desired stability, and the top thereof terminates in the outwardly and horizontally extending flange 11, which cooperates with a similar flange 12 formed on the bottom of the preferably cylindrically shaped hopper casing 13, secured thereto by the screw bolts 14 so that the hopper can be readily removed when desired. I preferably interpose between these flanges 11 and 12, a flange 15 forming the outer edge of the baffle 16, which is a sheet metal annulus preferably in the form of an inverted truncated cone, and which serves to prevent the possibility of any water splashing up to the carbide valve mechanism during the operation or transportation of the device. The bottom of the carbide holder is formed by the inverted truncated conical portion 17, which has the opening 18 at the bottom thereof through which the carbide escapes in the manner to be hereinafter described. This hopper bottom 17 will, of course, be secured in the casing 13 in any desired manner. Secured in a vertical side of the casing 13 is the

pressure regulator 19, and on the opposite side is secured the vibrator 20, which is connected by the pipe 21 with the purifying chamber 22, which is supported from the flange 12 by one or more bars 23 secured to the upper side of said flange and to the top of the purifier chamber. The opening 24 in the top of the casing 13, through which the carbide is passed in filling the hopper, is closed in any suitable manner, as by the mechanism indicated at 25, and it will be noted that when the screw bolts 14 are removed, the hopper casing 13 and all the connected parts may be removed without in any way interfering with their connections, so that the parts are readily accessible for adjustment and repair. The gas after passing through the purifying chamber 22 is carried off to the torch or other consuming unit through a flexible pipe 26 attached to a nipple on the top of the purifying chamber 22. The filler valve 27 may be of any desired construction, as well as the drain valve 28, and the customary sludge stirring apparatus is provided with the handle 29.

The pressure regulator 19, seen in section on an enlarged scale in Fig. 3, consists of the two halves 30 and 31 having the peripheral flanges between which are clamped the flexible diaphragms 32, by the screw bolts 33 which secure the two halves together. The diaphragms 32 are made rigid at their centers by the pair of discs 34 secured on the two sides thereof by the nuts 35 adjusted on the threaded end of the rod 36 which extends through the apertured boss 37 and through the short pipe 38 threaded at one end in the boss 37 and at the other end in the casing 13 to make a gas tight joint. A helically coiled expanding spring 39 is interposed between the adjacent disc 34 and the annular abutment 40 formed in the body 31 so as to tend to hold the diaphragm pressed outwardly. The other end of the rod 36 is provided with the fork 41 which is connected by a pivot pin with the lever 42 which is fulcrumed by a nut and bolt 43 between the pair of bars 44 which are secured at their ends by nuts and bolts to the lugs 45 and 46 which project toward each other from the inner face of the casing 13 and from the outer face of the hopper bottom 17. The lower end of the lever 42 is turned substantially at right angles, as shown, and has pivotally mounted thereon the mushroom

valve 47 which is shaped to cooperate with the aperture 18 in the bottom of the hopper and to close it completely under some conditions, or to be held a slight distance away from it under others, as will be hereinafter described. The valve 47 has a lug 48 formed on the under side thereof in which is screwed one end of the link 49, which is shaped, as best seen in Fig. 4, and has its other end extending through the short tube 50 threaded into the wall of the casing 13 and having its other end threaded in the T 51, the opposite end of which is closed by the nut 52. Threaded in the upper opening of the T 51 is the short tube 53 threaded into the bottom of the vibrator casing 54 which consists of a cup having the tubular portion 55 formed integral therewith and extending upward toward the top, as shown, so as to form a continuation, as it were, of the tube 53. A filling cup 56 threaded in the side of the vibrator casing 54 and having its upper end closed by the screw 57 forms a means of filling the vibrator cup to the level indicated, so that the bottom of the inverted cup or bell 58 will always be immersed in the water. This bell 58 is secured by nuts or otherwise, as shown, to the upper end of the rod 59 extending down through the part 55 and the tube 53 to connect with the link 49, preferably by having a loop on the bottom thereof through which the threaded end of the link 49 passes and has the nut 60 screwed thereon to secure the bottom of the rod 59 to the link 49.

In operation, it will be understood that the gas passing from the tank 10 through the pipe 50, T 51, pipe 53, is interrupted by the bell 58 until the pressure of the gas in the inside of the bell is sufficient to lift it up far enough so that the gas confined therein can suddenly escape beneath the bottom of the bell, allowing the bell to drop suddenly. This sudden downward movement of the bell is communicated by the rod 59 to the link 49, and serves to joggle or vibrate the valve 47 with the result that the fine carbide which is held between the edges of the aperture 18 and the top of the valve 47 is allowed to fall off of the valve and into the water in the generator. It will of course be understood that the amount thus discharged at each vibration of the bell 58 will depend upon the adjustment of the valve 47, which adjustment, of course, will be regulated according to the pressure of the gas which it is desired to secure. It will also be understood that while the amount of the discharge at each operation of the bell remains substantially the same, the rate of discharge is controlled by the frequency with which the bell 58 is vibrated, and this, of course, will be controlled by the rate of consumption of the gas generated.

Returning to pressure regulator 19, the

outer half 30 has the internally threaded boss 61 into which is threaded the tube 62 having secured in the outer end thereof the tubular end 63 of the fork 64, which has the pair of ears 65 in which is fulcrumed the handle 66, which is guided in its movement by the other side 67 of the fork. This handle has pivoted thereto the thrust rod 68 which extends through the tubular end 63 of the fork 64 and through the tube 62 to a point where it contacts, under ordinary adjustments, with the adjacent end of the rod 36. The tube 63 of the fork 64 has secured on its inner end the abutment ring 69, which has a shoulder 70 adapted to cooperate with the adjacent end of the heavy helically coiled contractile spring 71 having its other end cooperating with the adjacent disc 34, and I preferably provide a second helically coiled expanding spring 72 within the spring 71, the spring 72 being longer than the spring 71, and always in operation, whereas the spring 71 is not brought into play until the fork 64 is screwed in to nearly its limit.

In the operation of my device, the fork 64 is, when the apparatus is shut down or to be transported, screwed out to the position shown in Fig. 3, where the spring 71 is not in action and the spring 72 is so slightly compressed that the spring 39 opposed to it holds the diaphragm forced outward to a position in which the rod 36 has swung the lever 42 until the valve 47 is in contact with the aperture 18, thus closing the bottom of the carbide hopper and preventing any generation of the gas. When the apparatus is to be put in operation, it, of course, being understood that the tank is filled with water to the proper level, the handle 66 is swung back and forth a few times so that the rod 68 will shove the rod 36 inward to substantially its limit of movement, each inward movement removing the valve 47 from the aperture 18 a sufficient amount to allow a small amount of the carbide to be discharged, and a few strokes of the handle 66 is sufficient to produce some pressure, which will, of course, be indicated by the gage 73 connected to the casing 13 below the hopper bottom 17. The fork 64 is now screwed in by turning it, conveniently using the handle 66 to give additional leverage, until the contact of the end of the rod 68 with the adjacent end of the rod 36 is sufficient to thrust the rod 36 in to a point where the valve 47 is the sufficient distance from the aperture 18 to cause the proper amount of carbide to be discharged to hold the desired pressure. It will, of course, be understood that if the pressure becomes too great, it, cooperating with the spring 39 will serve to force the diaphragm 32 outward until the valve 47 is brought to the right distance from the aperture 18 to secure the desired

pressure. It will also be understood that during the normal operation of the apparatus, the lever 66 is adjusted so that the end of the rod 68 does not engage the rod 36,

5 and consequently the pressure of the generated gas and the spring 39 is opposed only by the pressure of the springs 72 and 71, the tension of which is, of course, regulated by the adjustment of the fork 64.

10 While I have shown and described my invention as embodied in the form which I at present consider best adapted to carry out its purposes, it will be understood that it is capable of modification, and that I do not 15 desire to be limited in the interpretation of the following claims except as may be necessitated by the state of the prior art.

While I have herein disclosed a generic invention, claimed generically in my afore- 20 said application No. 525,566, filed December 29, 1921, I do not herein claim any portion of said generic invention, but only the specific features not found or disclosed in the aforesaid application No. 525,566.

25 What I claim as new and desire to secure by Letters Patent of the United States, is:

1. In an apparatus of the class described, the combination with a liquid holder having a circular opening in the top thereof, of a cylindrical dry chemical holder casing adapted to be seated on said opening and secured to the holder, an inverted truncated conical shell secured in the casing to form a bottom thereof with a central discharge opening, and means for automatically controlling the feed of the chemical secured to and carried by said casing, said means consisting of a valve to cooperate with the central discharge opening, pressure controlled 35 means connected to the valve to control its position relative to the discharge opening, and a vibrator also connected to the valve and operated by the passage of the gas from the apparatus to vibrate said valve and thereby control the feed of the chemical.

40 2. In an apparatus of the class described, the combination of a liquid holder, of a dry chemical holder, a valve between said holders for discharging a dry chemical gradually into the liquid holder, a pressure regulator connected with said valve to control the extent of its opening and the consequent rate of feed of the chemical, a diaphragm in said regulator, a spring cooperating with said 45 diaphragm to control its position, means for adjusting the tension of the spring, a rod carried by the adjusting means and movable into contact with the diaphragm to control its position, and means for moving the rod 50 to initially start the feed independently of the automatic regulation.

60 3. In an apparatus of the class described, the combination of a liquid holder, of a dry chemical holder, a valve between said holders

for discharging a dry chemical gradually 65 into the liquid holder, a pressure regulator connected with said valve to control the extent of its opening and the consequent rate of feed of the chemical, a diaphragm in said regulator, a spring cooperating with said 70 diaphragm to control its position, means for adjusting the tension of the spring, a rod carried by the adjusting means and movable 75 into and out of contact with the diaphragm, and a lever pivoted on said means and having said rod pivoted thereto so as to constitute the load of the lever when it is used to operate the feed independently of the automatic regulation.

4. In an apparatus of the class described, 80 a pressure regulator consisting of a shell composed of two halves, a diaphragm secured at its edges between said halves, an operating rod secured to the center of the diaphragm and extending through and out of one of 85 said halves, an abutment threaded into the center of the other half, a helically coiled expanding spring interposed between said abutment and the center of the diaphragm, a rod sliding through said abutment and 90 having its inner end adapted to cooperate with the center of the diaphragm, and means to slide said rod in said abutment so that it may be moved entirely out of engagement with the diaphragm or used to vibrate the 95 diaphragm to operate the feed independently of the automatic regulation.

5. In an apparatus of the class described, 100 a pressure regulator consisting of a shell composed of two halves, a diaphragm secured at its edges between said halves, an operating rod secured to the center of the diaphragm and extending through and out of one of said halves, an abutment threaded 105 into the center of the other half, a helically coiled expanding spring interposed between said abutment and the center of the diaphragm, a rod sliding through said abutment and having its inner end adapted to 110 cooperate with the center of the diaphragm, and a lever pivoted on the outer end of said abutment and having said rod pivoted thereto so as to constitute the load of the lever.

6. In a device of the class described, the combination of a liquid holder, of a dry 115 chemical holder, a valve between said holders for discharging the dry chemical gradually into the liquid holder, a pressure regulator connected with said valve to control the extent of its opening and the consequent 120 rate of feed of the chemical, a rod extending from the pressure regulator through the side of the dry chemical holder toward said valve, a lever extending parallel to the conical bottom of the holder and fulcrumed between said bottom and the side through 125 which the rod extends, said lever having the rod pivoted to the power arm thereof

and the valve to the load arm, and means for vibrating the valve as the generated gas is used.

7. In an apparatus of the class described, the combination of a liquid holder, of a dry chemical holder, a valve between said holders for discharging the dry chemical gradually into the liquid holder, a pressure regulator connected with said valve to control the extent of its opening and the consequent rate of feed of the chemical, a vibrator chamber containing a liquid and a bell therein so

that the gas consumed has to escape in bubbles from beneath the edges of the bell, a vertical rod extending downward from the bell, a T in which the rod terminates, a connection from the T to the side of the dry chemical holder, a horizontal link connected at its outer end to the vertical rod in the T, and at its other end to the valve so that the movements of the bell vibrates the valve.

In witness whereof, I have hereunto set my hand this 25th day of June, 1926.

PARMER DORSEY.
